ARCH SUPPORT

Joseph C. Howell, Fort Lee, N. J.

Application April 8, 1936, Serial No. 73,316

8 Claims. (Cl. 36—71)

This invention relates to arch supports and has particular reference to improved arch supporting units for the metatarsal and longitudinal arches which units are so constructed and arranged as to permit of the longitudinal, angular and vertical adjustments thereof in order that the same may be selectively set to provide a corrective support for any deformity of the said arches.

10 The invention further comprehends resilient arch supporting units for the metatarsal and longitudinal arches which are independently adjustable and which includes means adapted to connect the units together and to engage with 15 the sole of the shoe for anchoring the same against longitudinal and angular movements.

The invention includes in one of its forms a flexible resilient arch plate, a tension plate underlying the arch plate, and connected therewith 20 for effecting upward arching of the arch plate, and means of connection between the said arch supporting units which permits of the relative adjustment of each unit with reference to the sole of the shoe so as to locate the same in any 25 desired position for supporting the arches.

More particularly the invention is directed to a means of connection between the arch supporting units which permits of pivotal adjustment of the metatarsal unit at a plurality of longitudinally spaced points, and means engaging with the metatarsal unit and the sole of the shoe for securing said adjustment.

The invention further includes in another of its forms, an arch supporting member comprising 35 upper and lower plies of material connected together at their edges to define a pocket therebetween for selectively receiving filler pads for effecting differential upward arching of the upper ply and means of connection between the 40 units which permits of the relative adjustment of the units and the pivotal adjustment of the metatarsal unit at a plurality of longitudinally spaced points, together with means engaging with the metatarsal unit and the sole of the shoe for 45 securing said adjustments with the units disposed in any desired position on the sole of the shoe.

With the foregoing and other objects in view, reference is now made to the following specification and accompanying drawings in which there 50 is illustrated several embodiments of the invention while the appended claims cover variations and modifications thereof which fall within the scope of the invention.

In the drawings:

55 Fig. 1 is a top plan view of arch supporting

units for the metatarsal and longitudinal arches illustrated in applied position with a portion of the shoe shown in dotted lines.

Fig. 2 is a bottom plan view of the metatarsal unit. 5

Fig. 3 is a sectional view taken approximately on the line 3—3 of Fig. 2.

Fig. 4 is a fragmentary sectional view taken approximately on line 4—4 of Fig. 1.

Fig. 5 is a bottom plan view of the longitudinal unit. 10

Fig. 6 is a sectional view taken approximately on line 6—6 of Fig. 5.

Fig. 7 is a bottom plan view of a modified form of the metatarsal and longitudinal units. 15

Fig. 8 is a top plan view thereof with parts broken away to illustrate the underlying structure of the metatarsal unit.

Fig. 9 is a longitudinal sectional view taken approximately on line 9—9 of Fig. 7. 20

Fig. 10 is a cross sectional view on line 10—10 of Fig. 8.

Referring to the drawings by characters of reference and more particularly to the form of the invention illustrated in Figs. 1 to 6 inclusive, the arch supporting device includes arch supporting units 10 and 11 for the metatarsal and inner longitudinal arches of the foot respectively. 25

The arch supporting unit 10 includes a spring metal plate 12 of general oval formation conforming generally to the region of the metatarsal arch of the foot with a convex upper surface and a concave lower surface. The plate 12 is provided with a longitudinally disposed slit 13 extending inwardly from the forward marginal edge thereof to a point adjacent the center and with a plurality of longitudinally spaced transversely extending slits 14 for increasing the flexibility of the plate. Underlying the plate 12 is a tension plate consisting of oppositely disposed 30

similar sections 15 contoured at their outer edges to the form of the side edges of the plate 12 and welded or otherwise secured thereto adjacent the lateral edges thereof and with reduced inwardly directed overlapping portions having aligned slots 35

16 therein for receiving therethrough a bolt 17 adapted to adjustably secure the sections 15 together for varying the stress therein for producing a differential transverse upward arching of the plate 12. The unit 10 also includes a plate 18 40

which underlies the spring plate 12 and which is welded or otherwise secured thereto adjacent the rear edge thereof between the sections 15 of the tension plate. The said plate is formed with a reduced forwardly extending neck portion which 45

overlies the sections 15 of the tension plate and is disposed between the tension plate and the arch plate 12 and terminates in an enlarged head 19 which underlies the forward portion of the arch plate 12 and extends slightly therebeyond to serve as a bearing for the slotted portion 13 of the arch plate. The said plate 18 also includes a rearwardly directed shank portion 20 provided with a plurality of corresponding longitudinally spaced pivot openings 21 disposed substantially on a line extending longitudinally thereof and with a plurality of corresponding longitudinally spaced arcuate slots 22 formed on radii with the pivot openings respectively as the centers thereof.

15 The arch supporting unit 11 includes a thin spring metal plate 23 which is longitudinally arched and overlies a portion of the heel of the shoe and extends forwardly therefrom under the inner longitudinal arch of the foot to a point adjacent to and at one side of the metatarsal arch supporting unit 10. The arch plate 23 has its highest point under the inner longitudinal arch and decreases in height with its inner curved edge and its opposite ends bearing upon the sole of the shoe. The said arch plate is formed with an upwardly curved lip 24 providing a support for the side of the foot adjacent the inner longitudinal arch and with a plurality of longitudinally extending slits 25 for increasing the flexibility thereof. The inner side edge of the arch plate 23 intermediate the ends thereof is provided with a lateral extension 26 formed with a plurality of pivot openings 27 disposed on a curve corresponding substantially to the curvature of the inner side edge of the shank portion of the shoe. The arch supporting unit 11 also includes a tension plate comprising oppositely disposed sections 28 and 29 welded or otherwise secured at their opposite ends to the ends of the arch plate 23 and with their inner ends disposed in overlapping relation and provided with a registering slot 30 adapted to receive a bolt 31 for selectively tensioning the tension plate so as to produce a differential upward arching of the arch plate 23.

30 The arch supporting units 10 and 11 are adapted to be positioned and selectively adjusted longitudinally of the sole of the shoe and angularly about a vertical pivotal connection by means of a bolt 32 extending through any one of the pivot openings 27 in the extension 26 of the arch supporting unit 11 and through any one of the pivot openings 21 in the extension 20 of the arch supporting unit 10, the bolt 32 being engaged by the nut 33 to secure the units in set relation and said nut and depending portion of the bolt being engaged in an anchoring recess 34 formed in the upper surface of the sole of the shoe. In order to secure the arch supporting units 10 and 11 against pivotal movement about the bolt 32 when the said units are connected together in set relation and the bolt is engaged in the anchoring recess 34 of the shoe, a bolt 35 is provided which extends through the corresponding arcuate slot 22 and is secured in position by the nut 36 and the said nut and depending portion of the bolt engaged in an anchoring recess 37 in the sole of the shoe. It is to be understood that the bolt 35 is adapted to selectively engage any one of the arcuate slots 22 in accordance with the setting of the bolt 32 in the corresponding pivot openings 21. The bolts 32 and 35 are provided with kerfed heads for engagement by a tool for loosening and tightening the same to provide the adjustment or readjustment desired.

35 In the form of the invention illustrated in Figs.

7 to 10 inclusive, the arch supporting unit 40 for the metatarsal arch of the foot and the arch supporting unit 41 for the inner longitudinal arch of the foot are of the same general shape respectively as the units embodied in the previous form. The arch supporting unit 40 includes upper and lower plies 42 and 43 of leather, rubber or any analogous flexible material which are secured together at their edges by stitching 44 or other equivalent means to define a pocket therebetween, one of the plies, preferably the lower ply 43, being provided with an arcuate slit 45 to define a mouth for receiving therethrough filler pads 54 for providing a differential upward arching of the upper ply 42. Secured to the outer surface of the lower ply 43 by any means, such as by stitching 46, is a flap 47 extending over the mouth opening 45 to serve as a closure therefor. The arch supporting unit 40 also includes a member 48 formed of a deformable material which is riveted or otherwise secured to the outer surface of the lower ply 43 adjacent the rear thereof and having a forwardly extending portion 49 adapted to engage with the flap 47 to secure the same in covering relation with the slot 45 and with the reduced free end thereof engaging in the keeper slot 50 in the flap 47 and retaining the extension 49 in engagement with the said flap.

The member 48 also includes a rearwardly extending, laterally offset portion 51 provided with a plurality of corresponding longitudinally spaced pivot openings 52 disposed substantially on a line extending longitudinally of the offset portion 51 and with a plurality of corresponding longitudinally spaced arcuate slots 53 formed on radii with the pivot openings 52 respectively as the centers thereof.

The arch supporting unit 41 includes upper and lower plies 55 and 56 of leather, rubber, or equivalent flexible material which are secured together by stitching or other equivalent means along their inner curved edges and at their ends and with their outer edges unsecured to provide a mouth opening therebetween and defining a pocket between the plies for receiving one or more filler pads 57 for producing a differential upward arching of the upper ply 55. The said unit also includes an underlying plate 58 of deformable metal or other equivalent material which is of the same general contour as the plies 55 and 56 and is riveted or otherwise secured to the outer surface of the bottom ply 56 with the marginal edges thereof spaced inwardly from the marginal edges of the plies 55 and 56. The plate 58 is formed with a substantially centrally disposed portion 59 which is adapted to be bent angularly to the plane of the body of the said plate and which portion is provided with a plurality of corresponding longitudinally spaced pivot openings 60 disposed on a curve corresponding substantially to the curvature of the inner side edge of the shank portion of the shoe.

The arch supporting units 40 and 41 are adapted to be selectively adjusted longitudinally of the sole of the shoe and angularly about a bolt 61 selectively engaging through any one of the pivot openings 60 of the central portion 59 of the plate 58 and through any one of the pivot openings 52 of the offset portion 51 of the member 48, the bolt 61 being engaged by a nut 62 for securing the units in set relation. The arcuate slots 53 are selectively engaged by a bolt 63, which bolt is secured in position in the slot by a nut 64, and the nuts 62 and 64 and the protruding downwardly projecting ends of the bolts 61 and 63 are 75

engaged in anchoring recesses in the sole of the shoe, identical with the anchoring recesses 34 and 37 in the previous form, for securing the arch supporting units 40 and 41 against pivotal movement with reference to the sole of the shoe. The upper ply 55 of the arch supporting unit 41 is formed with an extension 65 adapted to extend over the outer edge portion of the ply 56 to provide a closure flap for closing the mouth opening between the said plies and which extension 65 is provided with keeper tongues 66 for engagement in registering keeper slots 67 and 68 in the bottom ply 56 and the plate 58 for securing the flap in closed relation with the mouth opening.

15 What is claimed is:

1. An arch supporting unit including a member having an arched upper surface and a rearward extension provided with a plurality of longitudinally spaced pivot openings and arcuate slots, 20 and means adapted to engage with the sole of a shoe and extending respectively through a pivot opening and arcuate slot for selectively locking the unit in any desired position.

2. An arch supporting device comprising a pair 25 of arch supporting units each having an arched upper surface, means on one of said units provided with a plurality of corresponding longitudinally spaced pivot openings and slots, means on the other unit provided with a plurality of longitudinally spaced pivot openings adapted to align with the pivot openings in the other unit, and means adapted to engage with the sole of a shoe and extending respectively through aligned pivot openings in the units and through one of 30 said slots for selectively locking the units in any desired position.

3. An arch supporting device comprising a pair 35 of arch supporting units each having an arched upper surface, one of said units being provided with a rearward extension, having a plurality of corresponding longitudinally spaced pivot openings and arcuate slots, means on the other unit provided with a plurality of longitudinally spaced pivot openings adapted to be selectively registered 40 with the pivot openings in the other unit, and means adapted to engage with the sole of a shoe and extending respectively through registering pivot openings in the units and through one of 45 said slots for selectively locking the units in any desired position.

4. An arch support including a flexible arched plate having a plurality of longitudinally spaced transversely extending slots, a tension plate underlying the arch plate and connected therewith 50 for effecting the upward arching of the arch plate, a plate secured to said arched plate extending rearwardly thereof and provided with a plurality of corresponding longitudinally spaced pivot openings and slots, and means adapted to

engage with the sole of a shoe and extending respectively through a corresponding pivot opening and slot for selectively locking the unit in any desired position on the sole of a shoe.

5. An arch supporting unit including upper 5 and lower plies of material connected together to define a pocket therebetween having a mouth opening adapted to receive filler pads through said mouth opening for effecting a differential upward arching of the upper ply, one of said plies 10 being provided with a keeper opening, a tongue adapted to engage in said keeper opening for closing said mouth, means connected with one of said plies having a plurality of correspondingly spaced pivot openings, and means adapted to 15 engage with the sole of a shoe and extending through one of said pivot openings for selectively locking the unit in any desired position.

6. An arch supporting unit including upper 20 and lower plies of material connected together to define a pocket therebetween having a mouth opening adapted to receive filler pads there- 25 through for effecting a differential upward arching of the upper ply, and means for closing said mouth opening, one of said plies being provided with an extension having a plurality of spaced pivot openings and slots, and means engaging respectively with one of the pivot openings and slots and adapted to engage with the sole of a 30 shoe for selectively locking the unit in desired position.

7. An arch supporting unit including upper and lower plies of material connected together to define a pocket therebetween, the lower ply having 35 a mouth opening therethrough adapted to receive filler pads for effecting differential upward arching of the upper ply, said lower ply being provided with means for closing said mouth opening and having a rearward extension formed with a plurality of correspondingly spaced pivot open- 40 ings and arcuate slots, and means engaging res- pectively with one of the pivot openings and arcuate slots and adapted to engage with the sole of a shoe for selectively locking the unit in de- 45 sired position.

8. An arch supporting device including a flexible arch plate, a tension plate underlying the arch plate and connected therewith for effecting the upward arching of the arch plate, a plate secured to the arch plate adjacent the rear thereof 50 extending forwardly to underlie the forward edge of the arch plate and extending rearwardly there- 55 of and provided with a plurality of longitudinally spaced pivot openings and slots, and means adapted to engage the sole of a shoe and extending respectively through a corresponding pivot opening and slot for selectively locking the unit in any desired position on the sole of the shoe.

JOSEPH C. HOWELL.
